UNITED STATES PATENT OFFICE.

JOSEPH K. DEMETER, OF NEW YORK, N. Y.

WATERPROOF SHOE FOR USE IN COUNTER CONSTRUCTION.

Application filed March 16, 1923. Serial No. 625,682.

To all whom it may concern:

Be it known that I, JOSEPH K. DEMETER, a citizen of the United States, and a resident of the city of New York, borough of 5 Manhattan, in the county and State of New York, have invented new and useful Improvements in Waterproof Shoes for Use in Counter Construction, of which the following is a full, clear, and exact description.

10 This invention relates to waterproof shoes for use in supporting walls and was primarily designed for supporting the marble counter wall provided in soda fountains.

15 Generally the counters provided in conjunction with soda water fountains are constructed from marble. In such a construction the front wall of the counter is usually supported on the same floor as the 20 refrigerator. Salt water continually escapes from the refrigerator and spreads on the floor. This salt water is absorbed by the marble, causing chemical action and the deterioration of the marble. In a short 25 time the marble will begin to crumble, necessitating its replacement. The interruption thus caused in the use of the soda water fountain and the expense of replacement seriously interferes with business. Consequently, a means for protecting the marble and other similar materials has become very necessary.

30 The general object of this invention is the provision of a waterproof shoe for use in construction work to protect materials that are likely to be damaged by absorbing moisture.

35 This object is accomplished by clamping a plurality of plates and waterproof members together so as to present a groove for receiving the members to be protected, the waterproof members being positioned between the members to be protected and the source of destructive moisture.

40 This and other objects of the invention will be more clearly understood from the following detailed description and accompanying drawing.

45 The drawing shows a vertical section 50 through the waterproof shoe disclosing its construction.

55 Referring to the above-mentioned drawing, a soda water fountain 10 and a refrigerator 11 are shown mounted behind a counter 12. The top 13 and front wall 14 of the counter are constructed from marble. The

shoe, to be described hereinafter, is provided for protecting the front wall 14 from the salt water that usually escapes from the refrigerator. The invention includes an 60 inner plate 15 made from some material, such as slate, that will not absorb water to any great extent. A supporting block or plate 16 also made from slate or some similar material is provided. This plate 16, 65 which is about two-thirds of the height of the inner plate 15 and of less width than the front wall 14, is positioned parallel to said plate. A waterproof member 17 equal in height to the height of the plate 15 is positioned between the plates 15 and 16. A 70 Z-shaped waterproof member 18 is positioned on the opposite side of the plate 16 from the inner plate 15. The lower member of this Z-shaped waterproof member 18 75 rests on the floor or foundation 20 while the upper portion seats on the top of the plate 16. An outer plate 19, which is usually made from the same material as the front wall of the counter 14, is positioned on the lower portion of the Z-shaped waterproof member 18. This plate 19 extends parallel 80 to the supporting plate 16 and is of greater height. Openings 21 are drilled into the inner face of the plate 19 and packed with lead or some material adapted for receiving screws. Openings are provided in the plates 15 and 16 in alignment with the lower openings 21 in the plate 19, and the three plates 85 are clamped together by means of screws 23 which project through the openings in the plates 15 and 16 and engage in the material packed in the openings 21. Since the plates 15 and 19 and member 17 are higher than the plate 16 a groove is presented for receiving the front wall 14 of the counter 12, the sides of said groove being formed by the member 17 and the plate 19 and the bottom thereof by the upper laterally extending portion of the member 18. Openings are 90 provided in the upper portion of the plate 15 which align with countersunk openings in the lower portion of the wall 14. Bolts 95 24 are mounted in these aligned openings and serve as a means for attaching the counter wall 14 to the shoe. Openings are also provided in the counter wall which align with the upper openings 21 drilled in the plate 19, and screws 25 are projected through these 100 openings provided in the counter wall 14 and engage in the lead or other material packed in the upper openings of the plate 110.

19 thus attaching the front plate 19 to the counter wall.

Besides providing a means for attaching the front plate 19 to the plates 15 and 16, in order to form the shoe, the lead or other material packed in the openings 21 of the front plate serve to prevent the possibility of moisture being conveyed along the screws 23 or 25 to the marble plate 19. This adds 10 to the protection offered by the shoe and preserves the front plate 19 which normally would be the first to deteriorate. An examination of the shoe discloses that the marble portions of the structure are separated from the foundation or floor 20, on which the pools of water usually collect, by a waterproof member. This eliminates all possibility of deterioration in the marble, and preserves its original appearance and qualities. 20

I would state in conclusion that while the illustrated examples constitute practical embodiments of my invention I do not limit myself strictly to the exact details herein illustrated since manifestly the same can be considerably varied without departing from the spirit of the invention as defined in the appended claims.

Claims:

30 1. A counter construction including spaced face and inner plates, a supporting block disposed in the space between said plates and of less height than the same, a waterproofing member interposed between said block and inner plate and extending above the upper end of said block, a second waterproofing member having a main portion interposed between said face plate and the adjacent face of said supporting block 35 and having laterally extending portions one of which is disposed between a support and the lower edge of said face plate and the other of which engages the upper edge of said supporting block and the first-named waterproofing member, said other portion combining with the inner face of said face plate and a portion of the first-named waterproofing member to form the bottom and sides, respectively, of a groove, and a front 40 wall having its lower edge disposed in said groove.

50 2. A counter construction including a front wall, a supporting block below the lower edge of said front wall, face and inner plates arranged on opposite sides of said supporting block and combining therewith to form a groove for receiving the lower portion of said front wall, waterproofing members interposed between said block and face and inner plates and having portions thereof combining to form a lining for the bottom and side of said groove, one of said members also having a portion interposed between the face plate and support,

and means for securing said front wall, 65 plates and supporting block together.

3. A counter construction including a front wall, a supporting block below said front wall, face and inner plates arranged on opposite sides of said supporting block, 70 waterproofing members interposed between said supporting block and face plate, the combined thickness of said supporting block and waterproofing member being equal to that of said front wall, said waterproofing member having a portion interposed between said face plate and support, and a second waterproofing member interposed between said inner plate and said supporting block and portion of said front wall. 80

4. In a store counter construction having a front wall of a material subject to deterioration under liquid action and adapted to be placed upon a floor supporting a source of such liquid under said counter; the combination of a foundation for said front wall adapted to raise and support the upper section of the same a considerable distance from the floor, and an offset lower section of said front wall extending down in front of said foundation, together with a continuous sheet of liquid proof material extending under said front wall extension, up between it at said foundation and over the top of said foundation, whereby access of said liquid to any portion of said front wall is prevented. 90

5. A structure such as set out in claim 4 combined with an inner plate of material substantially impervious to said liquid, fastened to the back of said foundation and extending above the same along the rear of said upper section of said front wall. 100

6. A structure such as set forth in claim 4 combined with an inner plate of material, 105 substantially impervious to said liquid, fastened to the back of said foundation and extending above the same along the rear of said upper section of said front wall, and a second continuous sheet of liquid proof material inserted between said inner plate and said foundation and upper section of front wall. 110

7. In a store counter construction including a front wall of a material having a constituent subject to attack by certain liquids and placed upon a floor which supports a body of such liquid; the combination with said front wall, of hidden means for supporting the same out of contact with said floor, said means comprising a foundation plate behind said wall and liquid proof bodies concealed behind said wall and interposed between said wall, foundation plate, and the floor, and adapted to prevent the access of said liquid thereto. 115 120 125
